(57) **CLAIM**

The ornamental design for a latching mechanism for an electrical connector, as shown and described.

DESCRIPTION

FIG. 1 is a front, bottom, right side perspective view of a latching mechanism for an electrical connector with environmental structure shown;

FIG. 2 is a front, bottom, left side perspective view thereof;

FIG. 3 is a front, top, left side perspective view thereof;

FIG. 4 is a front, top, right side perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The broken lines in the figures show portions of the latching mechanism for an electrical connector and environmental structure that form no part of the claimed design.
